United States Patent Office.

RICHARD CALROW, OF MAMARONECK, NEW YORK.

Letters Patent No. 66,215, dated July 2, 1867; antedated June 22, 1867.

IMPROVEMENT IN INSULATOR-HOLDERS.

The Schedule referred to in these Letters Patent and making part of the same.

TO ALL WHOM IT MAY CONCERN:

Be it known that I, RICHARD CALROW, of Mamaroneck, county of Westchester, State of New York, have invented a "new and improved Insulator-Holder;" and I do hereby declare that the following is a full and exact description thereof, reference being had to the accompanying drawings, and to the letters of reference marked thereon.

Figure 1 is an end view of the insulator and block

Figure 2 is a side elevation of the same.

Figure 3 is a longitudinal section of the same.

A is the holder. b b are the clutches that hold the insulator. f is the flange on the holder. i is the screw that is turned into the block. C is the metallic covering on the block. d is the insulator. e is the lug on the insulator. g is the block to which the holder is fastened. h h' h'' are the flanges by which the block is attached to the building.

The nature of my invention consists in providing a neat and effective insulator-holder, that can be put on to metallic roofs without injury to the roofing by making holes in the same, and preventing the metallic covering from expanding and contracting without tearing or breaking.

Construction.

To enable others skilled in the art to make and use my invention, I will proceed to describe its construction and operation.

The holder A is made of malleable iron, or any other suitable material, with its clutches b b', flange f, and screw i, as shown in figs. 1, 2, and 3. The two clutches are left open at the top, so as to let the lug e on the insulator d pass through them. Then we provide a square block, g, of wood, or any other suitable material. The block g is then covered with tin or any other suitable material. The covering c is fitted on over the block, and soldered on so as to make it water-tight. The covering is left long enough to turn up and form the flange h h' h''. All of the several parts now being made and put together, the insulator is now ready for use.

Operation.

The "insulator-holder," after being made as above described, is taken on the metallic roof by the workman; the line of the lightning-rod or telegraph wire is determined, the line is then spaced off, and the blocks are then soldered on to the metallic roof, or made fast in any known way, without making holes in the roof.

Advantages.

The advantage of my invention consists in providing a reliable insulator-holder, that can be attached to any metallic roofing without making holes in the roof or roofing, and allowing the metallic roofing to contract and expand without any interference on the part of the "insulator-holder."

Claims.

What I claim as my invention, and desire to secure by Letters Patent, is—

The combination of the block g, metallic covering c, and the holder A, for the purposes set forth.

RICHARD CALROW.
